P. ARMSTRONG

PIPE WRENCH

Filed Nov. 29, 1926

FIG. 1.

FIG. 2.

INVENTOR:

PAUL ARMSTRONG,

BY
Robert Burns

ATTORNEY.

UNITED STATES PATENT OFFICE.

PAUL ARMSTRONG, OF CHICAGO, ILLINOIS, ASSIGNOR TO ARMSTRONG BROS. TOOL CO., OF CHICAGO, ILLINOIS, A CORPORATION OF ILLINOIS.

PIPE WRENCH.

Application filed November 29, 1926. Serial No. 151,401.

This invention relates to that type of pipe wrenches in which the movable wrench jaw and its adjusting sleeve nut are in pivotal connection with the stationary jaw member, 5 to permit limited opening movement of the jaws by hand in an application of the tool to a pipe or like article, an example of which forms the subject matter of Patent No. 1,495,751, issued to the Armstrong Bros. Tool 10 Co., as assignees of John V. Larson. And the present improvement has for its object:—

To provide a simple and effective resilient means whereby the movable jaw of a wrench 15 structure of the above mentioned type is yieldingly moved towards the companion stationary jaw, and which at the same time is adapted to prevent accidental separation of the operating sleeve nut from its open 20 pivotal mounting on the stationary wrench member when the movable member is removed from the structure for repair, replacement, etc. all as will hereinafter more fully appear. In the accompanying drawing:—

Fig. 1, is a side view of a pipe wrench of the above mentioned patented construction, with the present improvement in place.

Fig. 2, is an enlarged detail transverse 30 section on line 2—2 Fig. 1.

Like reference numerals indicate like parts in the two views.

Pipe wrenches of the present type comprise a main handle or stock 1 carrying at 35 one end a stationary jaw 2, and having fixed upstanding hook shaped cheek plates 3, in transverse spaced relation to provide a guiding channel for the screw threaded shank portion 4, of the movable wrench 40 member which carries to usual angularly arranged movable wrench jaw 5. Said hook shaped cheek plates 3 also provides a rearwardly open pivot socket for an annular end bead of the sleeve nut 6 by which the 45 movable jaw 5 is adjusted to and from the stationary jaw, as set forth in detail in the above mentioned Patent No. 1,495,751.

In addition the main or handle member 1 carries a fixed yoke 7 in spaced relation to the aforesaid cheek-plates 3, to hold the shank of the movable jaw against lateral

shift, as well as confine said shank to a normal extent of pivotal movement, as set forth in the aforesaid patent.

The material part of the present improvement in connection with a wrench structure substantially as above described comprises a detail formation and combination of parts as follows.

The rearward end of the operating sleeve 60 nut 6 of the movable wrench member is provided with a plain circular portion 6' adjacent to the usual knurled perimeter of the nut, with such circular portion 6' affording a bearing contact for the end of the spring 65 plunger, now to be described.

At the mid-width of the handle or stock 1, and in forward and adjacent relation to the aforesaid yoke 7, a receiving socket is formed, with such socket comprising an upper enlarged cylindrical portion 8 and a reduced lower cylindrical portion or bore 9 as shown in Fig. 2.

Within said socket, a plunger comprising 75 an upper enlarged cylindrical portion 10, and a lower reduced cylindrical portion 11, is arranged to slide, with its upper end, which is preferably of a tapering form having bearing contact against the circular surface 6' of the adjusting sleeve nut 6 aforesaid. 80

Intermediate of the shoulder formed at the meeting of the portions 10 and 11, and a like shoulder formed at the meeting of the portions 8 and 9 of the aforesaid socket, a coiled compression spring 12 is arranged, 85 the tendency of which is to force the plunger upward and attain a corresponding pivotal movement of the shank 4 of the movable wrench jaw 5, to maintain the jaw 5 in normal and required relation to the stationary 90 jaw 6 heretofore described.

With the described formation and association of parts, the operating sleeve nut 6 is effectively held in its pivotal position in the rearwardly open socket formation of the 95 cheek plates 3, when the movable jaw member 4, 5, is removed for repair, replacement, etc., and thus the delay and inconvenience of seeking and replacing a detached sleeve nut is avoided. In the present specific construction of the parts, the head portion 10 of the plunger that maintains the sleeve nut 6

in its operative position, is entirely shielded from accidental impacts which would act to release the holding engagement between the plunger and the sleeve nut, and in turn the like engagement between the sleeve nut and the cheek plates 3, of the structure.

Having thus fully described my invention, what I claim and desire to secure by Letters Patent, is:—

10 A pipe wrench comprising, a handle carrying a wrench jaw at one end, cheek plates secured to said handle in spaced relation to said jaw, and having a hook form providing a rearwardly open pivot socket, 15 a confining yoke secured to said handle in spaced relation to said cheek plates, a companion wrench jaw having a screw threaded shank adapted for movement between said cheek plates and through said confining yoke, an operating sleeve nut arranged between the sleeve plates and yoke and having at one end an annular bead adapted to effect pivotal engagement between the nut and

cheek plates and hold said nut from lateral displacement, said nut having a reduced peripheral portion remote from the annular bead aforesaid, a plunger formed with an enlarged end portion adapted for bearing contact with the reduced peripheral portion of the sleeve nut to hold said nut in its pivoted engagement with the aforesaid cheek plates and prevent detachment of the nut when the movable wrench member is removed for repair and the like, said plunger having a reduced end portion in aligned relation to said enlarged portion, the handle having a socket or recess formed with enlarged and reduced portions complementary to the plunger and adapted to slidingly receive the same, and a compression spring arranged in the enlarged portion of said recess and having bearing engagement with the enlarged portion of the plunger.

Signed at Chicago, Illinois, this 29th day of October, 1926.

PAUL ARMSTRONG.
